UNITED STATES PATENT OFFICE

ERNEST O. FREDERICKS, OF NEW YORK, N. Y., ASSIGNOR TO E. FREDERICKS, INC., OF NEW YORK, N. Y., A CORPORATION OF NEW YORK

ELECTRICAL TREATING APPARATUS

Original application filed October 27, 1927, Serial No. 229,141. Divided and this application filed March 28, 1930. Serial No. 439,613.

This invention relates to automatic time-controlled circuit-breaking devices, and particularly to that type of such devices in which an electrical treating apparatus after a desired period of time, is automatically shut off to avoid over-treatment; and is a division of my copending application Serial No. 229,141, filed October 27, 1927.

An object of the invention is to provide a device of the type described which will not only interrupt the circuit after a desired period of time, but will allow of a uniform treatment with the apparatus under varying voltage conditions in the power line.

Another object of the invention is to provide means ancillary to the time-control switch whereby the operator may adjust the time period to compensate for voltage variations in the power line.

Other objects of the invention will in part be obvious and will in part appear hereinafter.

The invention accordingly comprises the features of construction, combination of elements and arrangement of parts which will be exemplified in the construction hereinafter set forth, and the scope of the application of which will be indicated in the claims.

For a fuller understanding of the nature and objects of the invention reference should be had to the following detailed description taken in connection with the accompanying drawings, in which:

Figure 1 is a diagrammatic view of the wiring diagram of the novel apparatus connected to a power line and to a treating mechanism;

Fig. 2 is a plan view of one type of automatic time-control cut-off device to which is applied the ancillary dosage indicator described herein;

Fig. 3 is an enlarged detail view of the indicator per se; and

Fig. 4 is a diagrammatic view of the apparatus installed on a permanent-waving machine.

Referring to the wiring diagram shown in Fig. 1 of the drawings, the numeral 10 designates the leads of the power line; 11 the leads taken off from 10, and 12 the time-

control switch which interrupts one of the leads 11 and has a switch mechanism 13 and a clock mechanism 14; 15 designates a voltmeter bridged across the leads adjacent the switch 12; 16 the fuses, and 17 an electrical treating apparatus.

Although any desired type of time-control switch may be used without departing from the spirit of the present invention, a type which has been found to be particularly desirable is that known as the L-F treatment timer, Type T, manufactured by the Liebel-Flarsheim Company, of Cincinnati, Ohio. The present invention is not particularly concerned with the details of the automatic time-control switch, but, in general, it may be stated that such switches comprise a clock mechanism, such as 14 shown in Fig. 1, an adjustable time-setting device such as 18, which in the case of the L-F timer (see Fig. 2), 60 functions also as a winding mechanism, and a switch 13, which, in the L-F timer, is a toggle-switch, which is tripped by the clock mechanism and which when in its "off" position acts to stop the clock mechanism. 65

In accordance with the principles of the present invention, the voltmeter 15 shown in detail in Fig. 3 is bridged across the leads controlled by the switch and is provided with a dual scale 19. This scale bears the usual 80 voltage readings 20, particularly those voltages within a range of 30v or so on either side of the normal voltage of 110, and an auxiliary scale 21, registering the minutes' treatment required for a given dosage at any 85 particular voltage.

Although the apparatus provided by the present invention is adapted for use on any electrical treatment apparatus in which accuracy of dosage is desired, such as, for example, therapeutic machines, radiant heat and other types of lamps, Morse-wave generator, galvanic and sinusoidal apparatus and the like, it has been found to be particularly useful in connection with permanent- 95 waving machines.

If desired, the scale may indicate only treatment times as shown in Fig. 2 at 19', the same having been calibrated as above, or other scales of the dual type may be ar- 100

ranged for other types of treatment machines, but, in general, the principle is the same.

Furthermore, since the voltmeter can be used separately from the time-control switch as an indicator of the proper time for any desired dosage, it is to be understood that such use is within the scope of the present invention. In explanation of the scale figures given in Fig. 3, it might be here explained that the usual time of treatment with a permanent-waving machine when using a voltage of 110 is about eight minutes. The particular scale shown, therefore, is adjusted on this basis to compensate for variations in voltage. For example, if the voltmeter shows 117 volts when the circuit is closed, the proper time for treatment is indicated as seven minutes instead of eight, and the operator takes this into consideration either in setting the time-control mechanism when the voltmeter is used in combination therewith, or in shutting off the heater at times if the voltmeter only is used.

If desired, the dial of the voltmeter may also have printed thereon further instructions to the operator, as indicated at 29, such as "Add two minutes for fine hair and three minutes for extremely fine hair". The use of the voltmeter with the time scale eliminates guesswork, insures correct treatment under varying voltage conditions, and, when used in combination with the time-controlled switch, automatically cuts off the electricity at the end of the treatment, thus allowing the operator to utilize the intervening time in doing other work. Furthermore, the use of the present device has a psychological value, in that it assures the customer not only that the treatment will be correct, but that it will be cut off at the proper time, regardless of the whereabouts of the operator.

Referring further to Fig. 4, there is here shown a diagrammatic view of the apparatus installed on a permanent-waving machine of the type described in my Patent No. 1,678,249, issued July 24th, 1928, on my application, Serial No. 130,873, filed August 23, 1926. When applied to a machine of this type the lead 11 coming off from the switch 13 is replaced by two leads 11', which pass through independent switches 31 and fuses 16' and thence to the ring-connector 30, where they are attached to one of the semi-circular contact-ring sections 22 carrying the socket-members 23. The other lead 11, which is not interrupted, also passes to the ring-connector 30, where it is connected with the circular contact-ring 24, which carries the socket-members 25. Also, as is shown in my said copending application, the ring-contact members may be connected with pilot lamps 26, which indicate when circuit is established between either of the semi-circular rings 22 and the ring 24, and the de-

vice also may be grounded, as by the lead 27. The heating elements 17, as will be readily understood, in turn are connected to the contact-rings 22 and 24 by means of individual plugs 28. It is to be understood, of course, that this particular permanent-waving machine is mentioned by way of example and that any other type of machine may be used.

Since certain changes may be made in the above construction, and different embodiments of the invention could be made, without departing from the scope thereof, it is intended that all matter contained in the above description or shown in the accompanying drawings shall be interpreted as illustrative and not in a limited sense.

It is also to be understood that the following claims are intended to cover all of the generic and specific features of the invention herein described, and all statements of the scope of the invention which as a matter of language might be said to fall therebetween.

Having described my invention, what I claim as new and desire to secure by Letters Patent, is:

1. In combination, an electrical treating apparatus, an adjustable time-control switch controlling the same, and a voltmeter connected across the leads between the switch and the apparatus, said voltmeter having a scale thereon indicating the time of treatment necessary for a definite dosage under varying voltage conditions.

2. In combination, an electrical treating apparatus, an adjustable time-control switch controlling the same, and a voltmeter connected across the leads between the switch and the apparatus, said voltmeter having a dual scale, one portion of which indicates the voltage on the line, and the other portion of which indicates the time of treatment necessary under varying voltage conditions.

3. In an electrical supply system for use in connection with treating devices, the combination comprising an electric circuit adapted to supply energy to said treating devices, a series connected time switch, an electric intensity reading instrument connected across said circuit provided with an indicating hand and a dial having graduations thereon so coordinated with said circuit as to indicate the length of time necessary for the persistence of said circuit which will give a proper treatment of definite dosage under varying electrical conditions of said circuit.

4. In an electrical supply system for use in connection with treating devices, a circuit comprising a series switch and clock mechanism therefor, and a device provided with an indicating hand and a dial having graduations so coordinated with said circuit as to indicate the time interval during which said clock mechanism shall leave said switch mechanism closed, and the length of which is

necessary for the persistence of said circuit, which will give a proper treatment of definite dosage under varying electrical conditions of said circuit.

- 5 5. An electrical supply system for use in connection with an electrical treating apparatus, including an electrical supply circuit, a device comprising a series switch mechanism, a clock mechanism for controlling said
- 10 switch mechanism, and an electrical instrument provided with scales adapted to show the voltage being used and the time interval for which said clock mechanism must be set to give a proper treatment for a definite dosage under varying voltage conditions.
- 15 6. In an electrical supply system for use in connection with an electrical treating apparatus, including an electrical supply circuit, a device comprising electrical heating units, a series switch mechanism and a clock mechanism, an electric measuring instrument, a scale thereon graduated to read volts, and a second scale thereon, so disposed with reference to said first scale that said instrument
- 20 indicates the time interval for which the said clock mechanism is to be set to actuate said switch at the end of a heat instrument period necessary for a definite dosage under varying voltage conditions.
- 25 7. In combination, an electric circuit for a heating device, a clock adapted to be set to open said circuit after a predetermined time, and means for indicating the proper setting of said clock according to the voltage in said
- 30 circuit.
- 35 8. In combination, an electric circuit for a heating device, a clock adapted to be set to open said circuit after a predetermined time, means for indicating the voltage in said circuit, and means for setting said clock to operate at different times according to said voltage.
- 40 9. In combination, an electric circuit for an electrical heating device, a voltmeter in said circuit, a clock adapted to be set for opening said circuit after a predetermined time, and means for indicating the proper setting of said clock according to the operation of said voltmeter.
- 45 50 10. In a device of the class described, an electric circuit, a clock adapted to open said circuit at a predetermined time which may be varied with each operation of the device, a voltmeter in said circuit including an indicating hand, and a scale associated with said voltmeter whereby said hand automatically indicates the time for which said circuit should remain closed for a particular operation.
- 55 60 In testimony whereof I affix my signature.
ERNEST O. FREDERICKS.
